UNITED STATES PATENT OFFICE

CARL A. JOERISSEN, OF WASHINGTON, DISTRICT OF COLUMBIA, ASSIGNOR TO UNDERWOOD TYPEWRITER COMPANY, OF NEW YORK, N. Y., A CORPORATION OF NEW JERSEY.

TYPE-WRITING MACHINE.

961,238.

Specification of Letters Patent. Patented June 14, 1910.

Application filed March 9, 1909. Serial No. 482,221.

To all whom it may concern:

Be it known that I, CARL A. JOERISSEN, a citizen of the United States, residing in the city of Washington, District of Columbia, have invented certain new and useful Improvements in Type-Writing Machines, of which the following is a specification.

This invention relates to tabulating mechanisms of typewriting machines, etc.

The principal object of the invention is to provide simple means readily applicable to existing machines, for enabling any one of a plurality of sets of column stops to be brought into use. These stops are preferably formed upon the under edges of thin plate-like carriers which are adapted to engage the column-stop rack, and are placed at different points along said under edges, so that certain stops are out of line with others, and fall into two or more rows. The key-operated denomination stops upon the machine framework are provided with a guide-plate, which may be adjusted backwardly and forwardly, to bring the denomination stops into line with any selected row of column-stops, thus adapting the machine for different classes of tabulating work.

In the accompanying drawings, Figure 1 is a part sectional side elevation of an Underwood typewriting machine, embodying the present improvements; the denomination stops shown adjusted to their forward positions, to coöperate with the forward row of column stops. Fig. 2 is a perspective rear view of the column-stop adjusting-plate and its appurtenances. Figs. 3, 4 and 5 show column-stops in different positions upon the carrier plates, so as to fall into the three rows, seen at Fig. 1. Fig. 6 shows a carrier provided with a plurality of column-stops.

Upon a carriage 1 is secured a rack 2, along which are placed carriers 3, each having prongs 4, 5, to engage the teeth on the upper and lower sides of the rack. These carriers are in the form of thin forked plates, to fit between the rack teeth, and may be adjusted to any points along the rack; any suitable locking bar 6 being provided upon the carriage to engage shoulders 7 on the carriers, to retain them upon the bar 2.

Certain of the carriers are provided with forward column-stops 8, certain others with column-stops 9 in rear of those at 8, and still others with column-stops 10 in rear of those

at 9. It will be seen at Fig. 1 that the stops 8 form one row and the stops 9 another, and the stops 10 a third, said rows being in the same horizontal tier or plane, and all beneath the rack 2. It will also be understood that certain of the carriers may be provided with a plurality of stops, as seen at Fig. 6. Denomination stops 11 are provided upon the tops of upstanding rods 12, the latter pivoted or loosely connected at their lower ends at 13 to the rear ends of levers 14 fulcrumed at 15 bearing keys 16 at the front of the machine. These column stops project up through a horizontal plate 17, which is slidable rearwardly and forwardly, said plate retained upon a suitable bed 18 by means of keepers or guides 19 engaging the edges of the plate. The latter is provided with a finger-piece 20, whereby it may be drawn rearwardly together with the column stops, the latter vibrating freely about the pivots 13 either to the extreme rear dotted line position 12^a at Fig. 1, to co-operate with the row 10 of column stops, or to an intermediate position, to coöperate with the second row 9 of column stops. A spring detent 21 is provided to engage three notches 22 in the plate 17, to retain the same, together with the denomination stops, in either of the described set positions. The denomination stops are provided, as usual, with returning springs 23.

If the operator desires to use the forward row 8 of column stops, he simply depresses the keys 16 in the ordinary manner. But when he desires to use the middle or rear row of column stops, he grasps the handle 20, and pulls the plate 17 and the denomination stops back, as far as required, the click 21 snapping into the notches 22, to position the plate. Thus three different classes of tabulating work may be done without rearranging the column stops along the column stop rack 2; and it will be observed that the device may be applied to Underwood and other machines, with but little trouble and expense.

Having thus described my invention, I claim:

1. In a typewriting and tabulating mechanism, the combination with a carriage having a rack, of a series of carriers along the rack, said carriers having column stops at different points along their under edges, so that certain stops are out of line with others,

the stops forming a plurality of rows, a series of upstanding denomination-stop rods beneath said column stops, a guide-plate up through which the denomination-stop rods 5 project, means to guide said guide-plate in a forward and backward movement to bring the denomination-stops into line with any selected row of column stops, a finger-piece connected to said guide plate, and a detent 10 to hold said guide-plate where adjusted.

2. In a typewriting and tabulating mechanism, the combination with a carriage having a rack, of a series of carriers along the rack, said carriers having column stops at 15 different points along their under edges, so that certain stops are out of line with others, the stops forming a plurality of rows, a

series of upstanding denomination-stop rods beneath said column stops, a guide-plate up through which the denomination-stop rods 20 project, means to guide said guide-plate in a forward and backward movement to bring the denomination stops into line with any selected row of column stops, a finger-piece connected to said guide plate, a detent 25 to hold said guide-plate where adjusted, and key-operated levers to which said denomination-stop rods are loosely connected at their lower ends.

CARL A. JOERISSEN.
